J. WISNIEWSKI,
DANCING TOY,
APPLICATION FILED NOV. 5, 1919.

1,334,578.

Patented Mar. 23, 1920.

UNITED STATES PATENT OFFICE.

JOZEF WISNIEWSKI, OF BLOOMFIELD, NEW JERSEY.

DANCING TOY.

1,334,578.

Specification of Letters Patent. Patented Mar. 23, 1920.

Application filed November 5, 1919. Serial No. 335,904.

To all whom it may concern:

Be it known that I, JOZEF WISNIEWSKI, a citizen of Poland, residing at Bloomfield, in the county of Essex and State of New Jersey, have invented certain new and useful improvements in Dancing Toys, of which the following is a specification.

The primary object of the present invention resides in the provision of a figure toy of the dancing type wherein the jointed leg sections of the figure are adapted to move upon their connections in response to a pull exerted upon cords connected therewith to create the impression of dancing.

A further object of the invention is to provide a figure toy having movable legs and a movable arm adapted to be shifted by pull cord devices with the movable arm carrying a stick similar to a violin bow and movable over a mock violin supported by the other arm, and body portion of the figure.

With the above and other objects in view, the invention consists in the novel form, combination and arrangement of parts, herein fully described and shown in the accompanying drawing, wherein like reference characters indicate similar parts throughout the several views.

In the drawing,

Fig. 1 is a front elevational view of a toy constructed in accordance with the present invention, the front wall of the platform section being partially broken away and shown in section to illustrate the passage of the operating cords through the box platform,

Fig. 2 is a side elevational view thereof with the box platform thereof partially broken away and shown in section,

Fig. 3 is a horizontal sectional view taken on line III—III of Fig. 1, and

Figs. 4 and 5 are perspective views, respectively, of the arm and leg sections of the toy figure removed from the body portion.

Referring more in detail to the accompanying drawing, the toy is illustrated as embodying a wall or plaque 6 of any preferred design having a hook receiving opening 7 provided in the upper end thereof by which the device may be suspended. The lower end of the wall 6 carries a box-shaped platform upon the front face thereof, the platform embodying an upper wall 8, end

wall 9 and a front wall 10, while the lower side thereof is entirely open as illustrated in Figs. 1 and 2.

A dancing figure toy is mounted upon the plate 6 and comprises in detail a stud 11 having the body portion 12 rigidly secured to the outer end thereof and in spaced relation to the wall 6. The body portion 12 of the figure has the left arm 13 formed integral therewith, being illustrated as bent at the elbow with the outwardly projecting end 13' supporting an imitation violin 14 formed integral with the adjacent shoulder 14' of said body 12. The head 15 is formed at the neck end of the body and a suitable design is formed upon the body to represent the style of clothing desired.

The movable parts of the body included jointed leg sections and a swinging arm, the arm being shown in Fig. 4 and represented by the reference character 16 as being bent at the elbow and carrying a stick 17 in the end portion thereof to represent a violin bow. The shoulder portion of the arm 16 is provided with a pivot receiving opening 18 having another opening 19 formed therein for purposes presently to appear. Each leg is of identical construction and embodies a thigh section 20 having the lower section 21 thereof pivoted as at 22 at the knee portion while a pivot receiving opening 23 is formed in the upper end of the thigh section for mounting the same on the body 12 while an additional opening 24 is formed therein for purposes presently to appear.

In assembling the leg sections upon the body, pivot pins 25 carried by the body 12 pass through the opening 23 in the leg sections 20 with the foot of each leg resting upon the upper wall 8 of the box platform. The arm 16 is pivotally mounted upon the shoulder of the body 12 by having one end of the cord 26 knotted and passed through an opening in the shoulder of said body portion and through the pivot opening 18 in the arm, the knotted end of the cord being in rear of the body portion 12 with the free end of the cord then inserted through the opening 19 in the arm and being directed downwardly through the opening 8' in the upper wall 8 of the box platform to assume the position shown in Figs. 1 and 2. Operating cords 27 have adjacent ends passed through the leg openings 24 and knotted for retention therein with the other ends

directed through the box platform opening 8' to the point 29 where the three cords 26 and 27 merge into a single pull cord 30.

The weight of the arm and stick carried thereby as well as the legs will cause the same to assume a resting position at all times when the toy is out of use, the feet resting upon the upper wall 8 of the box platform and the arm assuming the position 10 with the stick carried thereby spaced from the violin 14. Considerable amusement may be obtained by operating the pull cord 30 to cause a simultaneous movement of the legs and arm, the impression being created of a 15 toy dancing synchronously with the playing of music. The speed of dancing and playing may be readily controlled by the operation of the pull cord 30 or if desired, the fingers of the operator may be inserted in the 20 lower open end of the box platform and each cord 26 and 27 individually operated.

While there is herein shown and described, what is believed to be the preferred embodiment of the invention, it is nevertheless to be understood that minor changes 25 may be made therein without departing from the spirit and scope of the invention as

claimed. The device may be constructed of any material desired, such as tin or card-board, and a calendar may be carried by the 30 front wall 10 of the box platform.

What is claimed as new is:—

1. A toy of the type described comprising a supporting wall, a figure mounted thereon, a box platform arranged beneath said figure, 35 an imitation violin supported in one arm of said figure, the other arm and legs of said figure being movably mounted and pull cord devices for operating the movable arm and legs.

2. A toy of the type described comprising a mounting wall, a figure supported thereon, an imitation violin instrument supported by one arm, the other arm and legs being 45 pivotally connected to the body portion of the figure and pull cord devices connected to the shoulder portion of the movable arm and the thigh portions of the movable legs for simultaneously operating the movable arm and legs and an imitation bow carried 50 by the hand portion of the movable arm.

In testimony whereof I affix my signature.

JOZEF WISNIEFSKI.
